UNITED STATES PATENT OFFICE.

JOHN E. McNAMARA, OF PETERSBURG, VIRGINIA, ASSIGNOR TO SEWARD TRUNK AND BAG COMPANY, OF PETERSBURG, VIRGINIA, A CORPORATION OF VIRGINIA.

WARDROBE TRUNK.

Application filed February 27, 1922. Serial No. 539,619.

To all whom it may concern:

Be it known that I, JOHN E. McNAMARA, citizen of the United States, residing at Petersburg, in the county of Dinwiddie 5 and State of Virginia, have invented certain new and useful Improvements in Wardrobe Trunks; of which the following is a specification, reference being had to the accompanying drawings.

10 This invention relates to wardrobe trunks having shoe boxes or like receptacles disposed in one section of the trunk, and particularly to means whereby the box or receptacle is supported in this section of the 15 trunk.

Wardrobe trunks are formed in two sections, one of these sections being formed to contain a plurality of drawers filling the section from top to bottom. The opposite 20 section of the trunk is provided at its upper end with means for hanging garments and at its lower end with a receptacle in the form of a box which ordinarily contains shoes. These receptacles are ordinarily arranged so as to be tilted and commonly 25 arranged so as to be removable from the section to which they are engaged. Many different devices have been utilized for the purpose of holding this shoe box in place 30 within the section and against longitudinal movement within the section without, however, preventing, when the trunk is opened, the ready tilting of the shoe box or its removal and replacement. Most of these 35 devices, however, are expensive to make and apply and many of them are ineffective for the purpose intended.

The general object of this invention is to provide means of a very simple and cheap 40 character whereby the shoe box may be held stationary within the trunk and yet permit the shoe box to be taken out and put in place with very little trouble.

A further object is to provide means of 45 a novel and simple form whereby the shoe box may be readily inserted without careful manipulation, said means acting to hold the shoe box securely in place against vertical movement when the trunk is closed 50 and against accidental or intentional outward swinging movement when the trunk is opened, and particularly which will hold the shoe box from accidental outward swinging movement unless the shoe box be initial-

ly raised, the device then acting to automatically release the upper end of the shoe box from its engagement with the walls of the trunk.

Other objects will appear in the course of the following description.

My invention is illustrated in the accompanying drawings, wherein:

Figure 1 is a perspective diagrammatic view of a wardrobe trunk illustrating my improvement applied thereto;

Figure 2 is a fragmentary vertical section through the trunk closed, showing the manner in which the shoe box is held in place from vertical movement when the sections are closed;

Figure 3 is a fragmentary perspective view of one end of the shoe box;

Figure 4 is a section on a horizontal plane through the lower portion of the trunk and through the shoe box.

Referring to these drawings, A designates the hanger section of a wardrobe trunk. This hanger section, as is well known, is hinged to the other section B of the trunk, which is filled with drawers, as before explained. I do not wish to be limited to any particular details of the trunk, as these may be of any suitable character.

Attached to the side walls a of the section A are the longitudinally extending strips 10 which are rectangular in cross section, though these strips might be formed in any suitable manner, these strips extending downward to the bottom of the section A. The strips 10 are formed in two sections 10^a and 10^b, the lower end of the section 10^a being downwardly and inwardly inclined and the confronting end face of the section 10^b being also downwardly and inwardly inclined parallel to the face of the section 10^a but slightly spaced therefrom.

Attached to the outer face of the section 10^a is a metallic strip 11 which extends downward and then downward and inward along the end face of the section 10^a and then upward against the inside face of this section, this upwardly extended portion being also attached to the section 10^a by means of screws, nails or other suitable devices. The upper end of the section 10^b is also protected by a metallic strip 12 which is attached to the outer face of the section 10^b, then extends diagonally downward over the upper

end face of the section 10^b and then down upon the inside face of the section 10^b, the downwardly extending ends of the metallic strips 12 being attached to the section 10^b by screws, nails or other suitable fastening devices.

The shoe box 13 may be formed in any suitable manner but is illustrated as having a rib 14 hinged to the bottom of the shoe box and detachably engaged with the top wall of the shoe box and with a handle 15 whereby the shoe box may be lifted. Attached to the end walls of the shoe box at the front thereof and extending vertically upward nearly to the top of the shoe box are metallic strips 16. These strips lie flat against the end face of the shoe box and are attached thereto by nails, rivets, screws, or other suitable means. The strips 16 are formed with laterally projecting flanges 17 extending the whole length of the strip 16 and these flanges 17 at their upper ends are bent downward and rearward, as at 18, and have the same angle as the slots formed between the sections 10^a and 10^b.

When the shoe box is in place, the downwardly extending tongues 18 extend into the slot between the sections 10^a and 10^b, while the flanges 17 bear against the faces of the strips 10. It will be seen that when the box is in place, the weight of the box and of its contents will tend to urge the box downward and the tongues 18 will, therefore, prevent any outward tilting movement of the box, while the flanges 17 prevent any inward movement of the box. When it is desired to tilt the box or remove it, the box is raised by the handle 15 and as it is raised the tongues 18 bearing against the upper wall of the slot between the sections 10^a and 10^b will be forced outward so that the mere act of raising the shoe box automatically causes the upper end of the box to shift outward until the tongues 18 become disengaged from the slots S. A mere lifting of the shoe box will, therefore, completely detach the shoe box from its engagement with the trunk section A. When it has been sufficiently raised, the shoe box may be turned downward on the floor, the lower ends of the flanges 17 acting under these circumstances as fulcrums for the box, or the box may be entirely removed from the trunk. When it is desired to replace the box, the box is lifted and brought toward the trunk until the ends of the tongues 18 strike against the strip 11. Then the box is lowered, whereupon the tongues will enter the slots S, and if then the box be released or still further lowered, the box will be caused to move downward and inward until it is again in its locked position. The weight of the box, as before remarked, and of its contents tends to hold the box in its locked position.

It will be further obvious that the box

cannot move upward unless the upper end of the box can move outward, and when the drawer section of the trunk is closed against the hanger section and, therefore, against the face of the shoe box, it will be obvious that the upper end of the shoe box cannot move outward and, therefore, the box is locked absolutely from any movement longitudinally of the trunk and thus cannot shift as the trunk is thrown around by the exigencies of travel. The flanges 17 which extend along the whole height of the box prevent the box from being forced inward and act to reinforce the shoe box and prevent its deformation.

I claim:

1. In an article of the character described, a casing open on one face and having inwardly projecting strips on said face having downwardly and inwardly inclined slots, and a receptacle adapted to be disposed within the case and having at its ends laterally projecting flanges, the flanges being formed with downwardly and inwardly extending tongues adapted to be engaged in said slots.

2. In an article of the character described, a casing open on one face and having inwardly projecting strips on said face having downwardly and inwardly inclined slots, and a receptacle adapted to be disposed within the casing and having at its ends laterally projecting flanges, the flanges being formed with downwardly and inwardly extending tongues adapted to be engaged in said slots, the ends of said receptacle having strips attached thereto angular in cross section, the strips having a length nearly equal to the height of the receptacle and being attached by their flanges to the receptacle, the upper ends of the strips being formed to provide downwardly and inwardly inclined tongues adapted to be engaged in said slots.

3. In a wardrobe trunk a drawer section, a clothes section and a shoe box adapted to be disposed in the lower end of the clothes hanging section flush with the outer face thereof, and single means on each side of the shoe box locking said shoe box in engagement with the sides of the section and preventing outward or upward movement of the shoe box, downward movement of the shoe box, or swinging movement of the shoe box when the sections of the trunk are closed.

4. In a wardrobe trunk, a drawer section, a clothes hanging section, a shoe box adapted to be disposed in the lower end of the clothes hanging section flush with the face thereof, and single means disposed on each side of said shoe box in engagement with the side walls of the sections preventing bodily outward, upward, downward or swinging movement of the box when the sections of the trunk are closed but permitting upward and outward bodily movement of the shoe

box to detach the shoe box from the side walls of the section when the trunk sections are opened.

5. In a wardrobe trunk, a trunk section formed at its ends with downwardly and inwardly inclined slots extending parallel to the side walls of the trunk section, and a box having at its upper end downwardly and inwardly inclined tongues adapted to engage 10 in said slots, the box having means limiting the inward movement of the box with relation to the trunk section.

6. In a wardrobe trunk, a trunk section having members extending toward each 15 other and disposed vertically at the sides of the trunk section, each of said members being formed with a downwardly and inwardly inclined slot, and a box adapted to be disposed within the trunk section having downwardly and inwardly projecting tongues 20 supported on the ends of the box and engageable in said slots and having means engaging said members and limiting the inward movement of the box within the trunk 25 section.

7. In a wardrobe trunk, a trunk section having its end walls provided at their front edges with vertically extending strips, said strips being downwardly and inwardly slot-

ted, metallic facing strips attached to the upper faces of said members and extending over the confronting faces of the slot, strips angular in cross section attached to the ends of the box and having their laterally projecting flanges flush with the front of the box, 35 said flanges at their upper ends being bent downward and inward to form tongues insertible into said slots.

8. In a wardrobe trunk, a trunk section having side walls and a box fitting between 40 the side walls and removable from the trunk section, means limiting the insertion of the box into the trunk section to a position where the front of the box is flush with the front of the trunk section, means locking the box to the 45 trunk section when the box is in a lowered position and preventing downward or swinging movement of the box when the trunk sections are opened but locking the box against 50 bodily upward or outward movement when the trunk sections are closed, said means causing the upward and outward movement of the box to release the locking engagement between the box and trunk section when lifting force is applied to the box. 55

In testimony whereof I hereunto affix my signature.

JOHN E. McNAMARA.
